UNITED STATES PATENT OFFICE.

GUY W. FITZGERALD, OF UNION, IOWA, ASSIGNOR OF ONE-HALF TO HARMON C. SHEAR, OF WATERLOO, IOWA.

TERMINAL CONNECTER.

Application filed April 14, 1926. Serial No. 101,998.

My invention relates more particularly to those terminal connecters which are made of strips or ribbons of spring metal folded back upon themselves into loop form and having circuit wire or terminal engaging portions upon their loop sides adapted to be placed in such relation by manually bringing the connector sides closer together as to afford circuit terminal receiving spaces between the terminal engaging portions. A wire end or circuit terminal inserted into a receiving space thus provided in a connector of this type serves to maintain the connector sides in contracted relation against the natural spreading action that is due to the resilience of the strip metal of which the connector is formed, with the result that the circuit terminal is held in mechanical and electrical assembly with the connector.

In the device of the prior art, one circuit terminal engaging portion is in the form of a kinked tongue inwardly struck from one side of the connector that constitutes the mounting base of the connector. This tongue is located in register with an opening formed in the remaining side of the connector which side is free to be depressed into a position in which the tongue will have its kinked portion projected sufficiently through said opening to provide the desired terminal receiving space between the kinked portion of the tongue and the depressed connector side. The connector is not only formed with an opening in its depressible side to receive the tongue, but is also formed with an opening where the tongue is struck from the base side, these openings weakening the connector. The tongue is so positioned that the flat side thereof, as distinguished from an edge, is engaged by the circuit terminal, the strain due to the resilient action of the connector being exerted upon the tongue in the same direction with the strain that was exerted in striking the tongue from the strip metal. As a consequence the tongue is apt to be broken away at its base.

In a connector of my invention, the circuit terminal engaging portions are so constructed and located that no openings are required in the sides of the connector. Instead of a single circuit terminal engaging tongue requiring the formation of a weakening opening in its construction, I employ two tongues at opposite longitudinal edges of one connector side, which may be a mount-

ing side, of the connector, these tongues being located abreast and constituting integral and angular lateral continuations of this connector side. The remaining side of the connector is disposed in register with and is movable in the space between said tongues, circuit terminal receiving spaces being formed between this remaining connector side and said tongues when the connector sides have been pressed sufficiently together.

In addition to the elimination of the weakening openings in the sides of the connector, which I thus effect, edge portions of the tongues are desirably presented to the inserted circuit terminal, these edge portions having a scraping or cutting action to remove current obstructing foreign matter from the terminal undergoing insertion. The spring pressure is also desirably exerted in the planes of the tongues rather than transversely to the plane of a single tongue, whereby danger of rupture at the junction of the tongues and the connector side carrying the same is overcome. A connector thus constructed may be made of lighter stock and of smaller dimensions than a connector of the prior art of similar strength.

The invention will be more fully explained in connection with the accompanying drawing in which Fig. 1 is a perspective view of the preferred embodiment of the invention in which a connector is shown in full lines in open or non-clamping adjustment, the terminal clamping adjustment of the connector being illustrated by the dotted lines as is also a wire or circuit terminal clamped thereby; Fig. 2 is a side view of the connector adjusted to clamp a terminal; Fig. 3 is a plan view of the connector as shown in Fig. 2; and Fig. 4 is a sectional view on line 4-4 of Fig. 3.

The connector illustrated is formed of a strip or ribbon of spring metal folded into the form of a loop having a base or mounting side 1 and an opposite free or depressible side 2 terminating in a finger hold 3 in the form of an outwardly deflected continuation of the connector side 2. The base side 1 of the connector may be formed with an opening 4 for the reception of the shank of a mounting screw. Tongues 5 are located abreast at opposite longitudinal edges of the base side of the connector and are integral and angular, or perpendicular, lateral

continuations of this connector side. The tongues project toward the manually adjusted connector side 2 and are spaced apart to permit this connector side to be depressed 5 into a position therebetween, as illustrated in Fig. 1 by dotted lines. The tongues are preferably in the shape of hooks in which case they have forward continuations 6 at their top sides that are so shaped as to afford hooking recesses 7. These hooking recesses and the juncture of the finger hold 3 with the balance of the depressible side 2, are so relatively located that circuit terminal receiving spaces are afforded between the 10 tongues and the depressible side of the connector, when this depressible side is sufficiently depressed. The circuit terminal 8, when caught between the tongues 5 and the sufficiently depressed connector side 2, serves 15 to hold this connector side in approached relation to the base side of the connector against the resilience of the connector whereby firm mechanical and electrical assembly 20 of the connector and circuit terminal is assured. The spring pressure exerted by the depressed connector side against the circuit terminal is resisted by the tongues in the planes thereof whereby any tendency to rupture the tongues where joined with the base 25 side of the connector is overcome. In other words, the strain on the tongues exerted by the depressed connector side 2 when the circuit terminal is in place is not in the same direction as the strain upon the metal occurring 30 in the formation of the tongues, with the advantage stated. In addition to this advantage, the edges of the tongues, rather than the broad sides thereof, preferably have engagement with the inserted terminal, the 35 contacting edges of the tongues having scraping or cutting action upon any current obstructing foreign matter upon the terminal thereby further improving the electrical assembly of the connector and terminal. By 40

employing two tongues the conductivity between the same and the terminal is doubled. 45

Where imperforate tongues having hooking recesses 7 are employed, the finger hold 3 may serve as a guide along which to slide the terminal into such hooking recesses, a feature of advantage where circuit connection is made in the dark. From the description and illustration of the invention, it will be observed that the tongues 5 are formed of lateral extensions of the loop side 1, said 50 tongues and loop side being formed of strip spring metal, whereby edge portions of the tongues are presented for engagement with the conductor applied thereto, the tongues being rigid in their relation to such conductor by virtue of their formation. 55

Having thus described my invention, I claim:

A connector formed of a strip of spring metal formed into a loop, one loop side of the connector having two tongues formed of lateral extensions of this loop side which are bent to project from opposite edge portions of this loop side toward the other loop side and spaced apart to permit this other loop side to be moved therebetween toward and from the first loop side, each of said tongues having a hook continuation at its upper portion extending along the connector and below which said other loop side may be depressed into a position to permit a wire crossing and moved along said other loop side to be held between this other loop side and the lower edges of said hook continuations, edge portions of the tongues being presented for engagement with the conductor applied thereto and the tongues being rigid in their relation to such conductor by virtue of their formation. 65 70 75 80

In witness whereof, I hereunto subscribe my name.

GUY W. FITZGERALD.
